EDWARD KIRBY BOTTLE, OF ELMIRA, NEW YORK, ASSIGNOR TO AMERICAN SALES BOOK COMPANY, LIMITED, OF TORONTO, ONTARIO, CANADA, A CORPORATION OF ONTARIO, CANADA

MANIFOLDING SALES BOOK

Application filed May 23, 1922. Serial No. 562,957.

This invention relates to manifolding devices and with respect to its more specific features to manifolding books, pads and the like.

One of the objects of the invention is to provide a simple manifolding pad or book wherewith five or more records at one writing may be made, the pad or book possessing practical advantages over other forms thereof.

10 Other objects will be in part obvious and in part pointed out hereinafter.

The invention accordingly consists in the features of construction, combination of elements and arrangement of parts which will be exemplified in the construction herein-after set forth, and the scope of the application of which will be indicated in the following claims.

In the accompanying drawings forming 20 part of this specification and wherein similar reference characters refer to similar parts throughout the several views.

Figure 1 is a perspective view of a manifolding device embodying the invention;

25 Fig. 2 is a diagrammatic side view of Fig. 1; and

Fig. 3 illustrates a modified form.

Referring now more specifically to the drawings and particularly to Fig. 1 thereof the numeral 1 indicates a pad of record leaves. 30 These leaves should be made of paper of such character that when leaves thereof are superposed one upon another with the interposition of transfer material, a writing made 35 upon an upper leaf will be transferred to the underlying leaves. In the embodiment now referred to the paper is relatively opaque and four opaque direct copies are made at one writing. It will be understood, however, that 40 transparent material, as tissue paper, may be employed.

The pad 1 is composed of a plurality of superposed record sheets bound together at one end by the staples 2. As all of these sheets 45 are alike the description of one will suffice. One of these sheets is shown in an open condition in Fig. 1 and is composed of the four leaves 3, 4, 5 and 6, the leaves 3, 5 and 6 being of substantially the same length and 50 width, the leaf 4 having an extended or stub

portion 7 for binding purposes, and being weakened along the line 8 in order that it may be readily torn from the stub portion.

Each of the record sheets is formed from a strip which is first folded along the line 9 to provide a folded record sheet of two plies. Thereupon this folded sheet is again folded intermediate its ends on lines parallel with the line 9 as generally indicated at 10, so as to provide the four relatively superposed record leaves 3, 4, 5 and 6 above referred to.

To the underface of the record leaf 6 at the free end thereof is pasted a supplemental, preferably transparent, record leaf 11, the pasted area being indicated at 12. The supplemental leaf 11 lies in superposed relation to the original leaf 3, although separated therefrom by the leaves 5 and 6, and when the book is set for operation as illustrated in Fig. 1, this supplemental leaf is also in superposed relation to the four leaves 3, 4, 5 and 6. The numeral 13 indicates a backing which may be of pasteboard or other relatively stiff substantial material, and the bound end of the pad 1 is held to the backing 13 by prolonging 55 the staples 2 for the purpose. The numeral 14 indicates a support leaf, also of stiff material as pasteboard or metal, the support leaf 14 being hinged or otherwise flexibly connected to the backing 13 on an axial line 30 parallel to and remote from the bound end of the pad 1. Thus it will be perceived that the pad 1 lies smoothly on the relatively stiff backing 13 and may rotate therewith on the support leaf 14.

The numerals 15 indicate the leaves of a supplemental pad held to the support leaf 14 along a line parallel to the bound end of the pad 1. The record leaves 15 of the supplemental pad are preferably transparent and may be composed of tissue paper and the supplemental pad may be held to the support leaf 14 by staples 16. The support leaf 14 projects or extends beyond the end of the backing 13 adjacent the bound end of the pad 1, so that the leaves 15 may be disposed in operative manifolding relation to those of the pad 1. In Fig. 1, one of the leaves 15 of the supplemental pad is shown in relative operative position.

In the present embodiment the transfer material, which is adapted to transfer inscription from one to another of the superposed record leaves, includes the transfer leaves 17 and 18. These leaves may be bound 5 with the record sheets of the pad 1 and they work from the bound end of the pad into superposed relation with each other and with the record leaves of the uppermost set of four record leaves comprised in each record sheet 10 of the pad 1. One of the transfer leaves, in the present embodiment the lower transfer leaf 17, is of sufficient length to extend across the fold line 10, this fold line being consequent from folding the two ply folded sheet in to the four ply sheet, as before referred to. In this wise it will be noted that the transfer leaf 17 is adapted to lie on the record leaf 4 and beneath the record leaf 3, the transfer 15 leaf 17 being folded on the line 19 which is parallel to the fold line 10. The other, the upper transfer leaf 18, is of a length to lie between the folds consequent from folding the two ply sheet into the four ply sheet; that 20 is, in consequence of the intermediate folding of the uppermost record sheet of the pad 1. 25

It will be understood that in Fig. 1 the record sheets and the transfer leaves are illustrated in open position, the arrangement 30 being diagrammatic for the purpose of clearly disclosing the relative positions of the parts. In operative condition the leaves will, of course, be flattened out so as to provide a proper disposition of the leaves for the mani- 35 plementing operation. In connection with the arrangement illustrated in Fig. 1 it may be observed that certain advantages follow by arranging the supplemental pad 15 to work from the side of the pad 1 instead of from the end thereof. This modification is dia- 40 grammatically illustrated in Fig. 3.

In Fig. 2 the arrangement is the same as in Fig. 1 except that five copies only are desired and hence the supplemental pad 15 and the 45 support leaf 14 are omitted.

Fig. 1 diagrammatically illustrates the book with the leaves operatively set for the purpose of making six copies at one writing. Of course the leaves will be flattened out in 50 the actual book. Inscription made upon the opaque original leaf 3 will be transferred direct to the opaque duplicate leaf 5, the opaque triplicate leaf 6 and opaque quadruplicate leaf 4. Reversed inscription will be ef- 55 fected upon the transparent supplemental leaves 11 and 15. After inscription the backing 13 is rotated on its axis 30 so as to cause the supplemental leaf 15 to be withdrawn from manifolding position and drop upon the 60 support leaf 14, whereupon reverse rotation of the backing 13 will cause it to lie upon the inscribed leaf 15, and hold it and protect it. Thereupon the leaves 3 and 5 are thrown back, (to the right, Fig. 1,) the transfer leaf 65 18 lifted, and the leaves 5 and 6 together with

the supplemental leaf 11 thrown back (to the right, Fig. 1) whereupon the inscribed set of leaves may be detached from the pad 1 by tearing along the weakened line 8. Subsequently the leaves 3, 4, 5 and 6 may be torn from each other and distributed as desired. It will be noted that supplemental leaf 11 will remain attached to the leaf 6 during the aforesaid operations, but may be torn therefrom when desired. 70

Thus by the above described construction are accomplished among others the objects hereinbefore referred to. 75

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. 80

Having described my invention, what I claim as new and desire to secure by Letters Patent is: 90

1. In a manifolding pad, in combination, a set of record leaves bound into the pad, transfer material having a binding, said set including a record sheet folded along a fold, the folded sheet being folded intermediate its ends on a line parallel to the first mentioned fold to provide four relatively superposed record leaves, said transfer material including transfer leaves supported in a position to work from the bound end of said pad into superposed relation with each other and with the record leaves of said set, one of said transfer leaves being of sufficient length to extend across the fold line of the uppermost record sheet consequent from said intermediate folding, and into overlapping manifolding relation with the record leaves remote from said binding, and another of said transfer leaves being of a length to lie between said bound end of the pad and the folds consequent 100 from said intermediate folding, said record sheet including a transparent record leaf pasted at the free end thereof and adapted to lie in contact with the upper face of said first mentioned transfer leaf, which face is 110 provided with transfer material, a backing to which the bound end of said pad is attached, a support leaf hinged to said backing remote from said bound end, and a supplemental pad of tissue leaves held to said support leaf along a line parallel to the bound end of the first mentioned pad, the leaves of said supplemental pad being relatively arranged for superposition relative to the leaves of the other pad and for engagement in manifolding relation with the upper face of said second mentioned transfer leaf, which is coated with transfer material for this purpose. 115

2. In a manifolding pad, in combination, a 120

set of record leaves bound into the pad, transfer material having a binding in the pad, said set including a record sheet folded transversely to provide a fold and the sheet thus folded being folded transversely intermediate its ends on a line parallel to the first mentioned fold to provide four relatively superposed record leaves, said transfer material including transfer leaves working from the bound end of said pad into superposed relation with each other and with the record leaves of said set, one of said transfer leaves extending from the binding across the fold lines of the record sheet provided by said intermediate folding and into overlapping manifolding relation with the record leaves remote from said binding, and another of said transfer leaves being of a length to lie between said bound end of the pad and the folds consequent from said intermediate folding and a transparent record leaf pasted at the free end of said record sheet and relatively positioned so as to lie in contact with the upper face of said first mentioned transfer sheet which is provided with transfer material.

In testimony whereof I affix my signature.
EDWARD KIRBY BOTTLE.
